John Reed Littell,

UNITED STATES PATENT OFFICE.

JAMES A. WHEELER, OF SOMERSET COUNTY, NEW JERSEY.

FIREPROOF FLOOR.

1,268,307.

Specification of Letters Patent.

Patented June 4, 1918.

Application filed October 11, 1912, Serial No. 725,281. Renewed September 25, 1917. Serial No. 193,195.

To all whom it may concern:

Be it known that I, JAMES A. WHEELER, a citizen of the United States, and resident of the county of Somerset, in the State of New Jersey, have invented certain new and useful Improvements in Fireproof Floors, of which the following is a specification.

This invention relates to fireproof floors, and it has for its object to provide a simple and improved floor construction which can be readily and economically placed in position, which will provide an attractive surface capable of various designs and coloring as desired, which will afford yielding and non-slipping characteristics approximating those afforded by a wood or lumber flooring, which will have the maximum degree of fireproof and moisture-proof qualities, and which will furthermore possess advantages in point of durability, strength, effectiveness and general efficiency.

Usually, the floor structure in fireproof building constructions has been formed by a base of cementitious material or concrete carrying a surface of wood or tiles. When a wood surfacing is thus employed, furring strips have usually been laid in the plastic base and ordinary flooring lumber has been secured to such strips and laid in the usual manner. Such a construction as that just described is not only lacking in fireproof characteristics, but is also disadvantageous in cases of imperfect connection between the wood surfacing and the plastic base. When such floor structures have employed a tile or stone surface, the tiles or slabs have been laid directly in the plastic base, but this construction is also lacking in the maximum of fireproof characteristics, as natural stone slabs or tiles are liable to disintegration under the action of heat, as are also artificial ceramic tiles or slabs, and furthermore in such constructions the tiles or slabs are apt to work loose from the base.

My improvements are designed to overcome all of the objections pertaining to previous constructions as above noted and to provide an improved flooring which is not only absolutely fireproof and effectively maintained in fixed and permanent connection with the plastic base, but which, while it is adapted for a wide range of surface designs and effects, can be so employed that it will simulate an ordinary wood flooring.

In the drawings—

Figure 1 is a top or plan view of a section

of a fireproof floor constructed according to one form of my invention and improvements.

Fig. 2 is a detail cross-section, on an enlarged scale, taken on the line $x-x$, Fig. 1.

Fig. 3 is a top or plan view of a section of a fireproof floor constructed according to another form of my invention and improvements.

Fig. 4 is a detail cross-section, on an enlarged scale, taken on the line $y-y$, Fig. 3.

Fig. 5 is a top or plan view of one of the sections of a fireproof floor surface, as the same may be employed under one form of my invention and improvements.

Fig. 6 is a bottom or plan view of the under side of the construction shown in Fig. 5.

Corresponding parts in all the figures are denoted by the same reference characters.

Referring to the drawings, 1 designates the cementitious or concrete base of the floor structure as usually laid in fireproof building constructions, the base being placed while in plastic condition so that it afterward sets and hardens. 2 designates the improved surfacing which is carried by said base, as comprised in my invention and improvements.

The surfacing 2 is formed in its entirety of a fireproof and non-fragile composition which produces a rigid body undeformable by heat. The composition having these characteristics, from which the members of the surfacing 2 are formed, may be of any suitable materials adapted to be mixed into a plastic substance which is molded into desired shape, such as slabs or boards, and then compressed and dried in a rigid structure. For instance a fibrous reinforced plastic material, comprising asbestos as the fibrous element mixed with a filler or base of crushed burnt clay or analogous substance and combined with a chemical fireproof binder, may be employed for the plastic mass which is pressed or molded into the boards or slabs from which the surfacing 2 is formed.

I prefer, however, in constructing the improved floor surfacing as comprised in my present invention and improvements, to employ a solidified compound consisting of a suitable filler, such as burnt clay crushed into small particles or into a pulverous condition, mixed with a suitable amount of asbestos or analogous substance of fireproof quality, the mixture being combined with a soluble fireproof binder, such as silicate of

soda, which is preferably in relatively small proportion, to produce a plastic substance, which moist plastic substance is molded into the desired shape, such as slabs or boards, and the molded article is subjected to heat and requisite pressure to dry and compress the same to the desired degree of density.

The improved surfacing of the floor structure, as comprised in my invention and improvements, thus has not only absolutely fireproof and non-fragile characteristics, but is rigid and undeformable by heat and furthermore possesses absolutely moisture-proof qualities and the degree of yielding and non-slipping characteristics which are desirable in a floor structure.

The distinctive characteristics of the fire-proof and non-fragile body composition of the surfacing 2, rigid and undeformable by the action of heat, are an important feature in the fireproof floor constituting my present improvements. For instance, ceramic tiles or artificial stone slabs are of fragile nature and liable to disintegration under the action of heat, and it is furthermore necessary that they be usually of excess thickness to impart the desired degree of strength and operative service, whereas in contradistinction the improved surfacing 2 as above set forth, formed of a fibrous reinforced plastic material or composition having the characteristics above described, resists any action of heat and may be laid in comparatively thin strips. It will also be noted that the slabs or boards constituting the improved surfacing 2, formed of artificially united substances solidified to resist strain and having the desired degree of density, and having the fireproof and moisture-proof and non-fragile characteristics and the rigid and undeformable qualities under the action of heat, constitute an artificial floor surfacing which is capable of all the uses in which wood is ordinarily employed, simulates a wood flooring, and may be secured by driven nails or otherwise worked in the same manner as wood.

In the preferred features of construction, as herein illustrated, the surfacing 2 is constituted by two thicknesses, the under one of which, as at 3, is a base slab or board, while the upper thickness, as at 4, forms the top surface. Both the under and top thicknesses 3 and 4 are formed of the fireproof and non-fragile and rigid and undeformable composition as above set forth, so that the surfacing 2 has the same qualities in its entirety, and the top thickness 4 is secured in connection with and over the top surface area of the under thickness 3 by a suitable adhesive, as at 5, or in any other adopted manner.

The dimensions of the sections of the surfacing 2, with relation to the entire floor

area, may be as desired. For instance, the under slabs or boards 3 may be of desired size to form floor-surfacing sections, each of such sections carrying a plurality of the top slabs or boards 4, and thus the top surface 4 will represent small sections in desired designs to simulate ordinary flooring or tiles and the under slabs or boards 3 will be in sections respectively having dimensions of relatively larger area.

In Figs. 1 and 2, I have shown one of the preferred forms of floor construction, in which the under slabs or boards 3 are formed in sections of relatively large area, which sections 3 respectively carry at their top surface a plurality of slabs or strips 4 laid parallel and in series to simulate ordinary strips of wood flooring. In Figs. 3 and 4, I have illustrated a construction similar to that shown in Figs. 1 and 2, in which relatively large under sections 3 respectively carrying a plurality of top parallel slabs or strips 4 are laid at right-angles, so that the strips 4 upon one slab section 3 run at right-angles to the top strips of the adjoining slab section, thus simulating a parquetry design of flooring. In Figs. 5 and 6, I have illustrated one section of a floor surface in another form of construction according to my invention, in which the section is constituted by an under slab or board 3 carrying at its top surface a plurality of slabs 4 which in configuration and relative arrangement simulate a tile floor surface in fanciful design, it being understood that the complete floor surface is formed by a plurality of such under sections 3 relatively placed to carry out the desired configuration or design of the composite floor surface.

The abutting edges of the plurality of top slabs or strips 4 which are carried by the relatively large under slab or board 3 are preferably secured in connection, by a suitable adhesive, as at 6, or in any other adapted manner, and the abutting edges of the respective sections which are constituted by the relatively large under slabs or boards 3 are preferably likewise secured together, in the organization of the complete floor structure, as shown at 7 in Figs. 2 and 4. The top slabs or strips 4 are preferably suitably colored, either uniformly, as when the floor is designed to simulate a wood flooring or a linoleum or analogous surfacing, or variably, as when the floor surface is designed to simulate an ornamental tiling or mosaic. Such coloring preferably exists throughout the body mass of the slabs or strips 4, and may be effected by mixing a suitable pigment or coloring matter with the composition of which the slabs or strips are formed before the same are molded and dried and compressed in finished condition.

In practice, the assembling of the under slabs or boards 3 and the top slabs or strips

4 in secured connection adhesively or otherwise, to produce the composite rigid structure constituting the section of the floor surface, may be effected under pressure in a 5 suitable press or other adapted apparatus.

It will be noted that in the double thickness construction as above described, the association of a plurality of top slabs or strips 4 in connection with the under slab 10 or board 3 produces in effect a laminated surfacing structure, which laminated conditions materially enhance the strength of the surfacing and its effective resistance to strains.

15 The surfacing sections of the improved flooring are secured preferably in direct connection with and carried by the main cementitious or concrete base 1, and my improvements comprise means for the secure and 20 permanent interlocking of the surfacing with said base. In the preferred construction for this purpose, the under slabs or boards 3 of the floor sections are provided with perforations, 8, preferably undercut, 25 as at 9, forming undercut or dovetail recesses in which the plastic of the cementitious or concrete base 1 will firmly engage and interlock with the surfacing floor sections. These perforations 8 preferably extend entirely 30 through the slabs or boards 3, so that the base of the recess is formed by the under side of the upper slabs or strips 4.

In the practical construction of the improved floor structure, the surfacing 2 is 35 applied to the main base 1 while the latter is in plastic condition, so that the cementitious or concrete material embeds in the recesses constituted by the perforations 8 and sets and hardens therein, thus securely 40 and permanently binding and locking the surfacing 2 in connection with the main base 1.

It will also be understood that in the construction of the floor surfacing sections in 45 the various forms as indicated in Figs. 1 to 6, inclusive, in which the two thicknesses 3 and 4 are employed, the under slab or board 3 may carry a single top slab or board 4 of corresponding area, under some circumstances of construction, in lieu of a plurality of slabs or strips 4, and that the sections constituted by the double thickness of slabs or boards 3 and 4 of corresponding 50 area may be of any desired configuration 55 to produce a composite floor design.

It will further be understood that, within the purpose and scope of my improvements, the surfacing 2 may be secured in connection with the main floor base 1 in any suitable 60 or adapted manner and under various struc-

tural conditions. For instance, the surfacing 2 may be worked or employed in the same manner as ordinary wood.

The advantages of my invention and improvements will be readily understood. The 65 improved floor provides in maximum degree not only fireproof and moisture-proof qualities, but is rigid and undefeatable by the action of heat, non-fragile and durable, and possesses the advantages of comparative 70 expensiveness and facility in manufacture and laying. The surfacing affords all of the desired non-slipping qualities and conditions of tread, and the construction and arrangement enables not only the simulation 75 of ordinary wood or tile but permits of a wide range of surface design.

I do not desire to be understood as limiting myself to the detail construction and arrangement of parts as herein shown and 80 described, as it is manifest that variations and modifications therein may be resorted to, in the adaptation of my invention to varying conditions of use, without departing 85 from the spirit and scope of my invention 90 and improvements. I therefore reserve the right to all such variations and modifications as properly fall within the scope of my invention and the terms of the following claim.

Having thus described my invention, I 95 claim and desire to secure by Letters Patent:

An improved fireproof floor surfacing, comprising a cementitious base, a top surface formed of a plurality of sections each 95 consisting entirely of a solidified fireproof and non-fragile composition which is rigid and of low heat conductivity and undefeatable by heat and each of said sections being formed of a plurality of slabs or strips 100 compositely secured together, and a plurality of sections intermediate of said top-surface sections and said cementitious base and each 105 consisting of a solidified fireproof and non-fragile composition which is rigid and of low heat conductivity and undefeatable by heat, each of said intermediate sections having an area underlying a plurality of the slabs or strips which compositely form the respective top-surface sections and being secured to 110 the under surface thereof and provided with means for securing an interlocking connection with the cementitious base.

In testimony whereof I have signed my name in the presence of the subscribing witnesses.

JAMES A. WHEELER.
